UNITED STATES PATENT OFFICE.

JOSEPH PASTOREL, OF ASBURY PARK, NEW JERSEY.

UNSINKABLE BOAT.

1,010,309.

Specification of Letters Patent. Patented Nov. 28, 1911.

Application filed September 8, 1911. Serial No. 648,284.

To all whom it may concern:

Be it known that I, JOSEPH PASTOREL, a citizen of the Republic of France, and a resident of Asbury Park, in the county of 5 Monmouth and State of New Jersey, have invented a new and Improved Unsinkable Boat, of which the following is a full, clear, and exact description.

My invention relates to unsinkable boats, 10 and its object is to produce a vessel of this type which will be lighter, faster and better able to resist damage than other vessels of the same description.

To this end I construct the frame of my 15 unsinkable boat of hard rubber, and cover it with sheets of rubber or rubber cloth in such a way as to form a number of independent air-tight compartments which can be inflated to increase the buoyancy of the 20 boat. The elasticity of the materials employed enables the structure to incur severe blows and shocks, because, when subjected to rough usage, the boat will yield instead of breaking, as it undoubtedly would in case 25 common material, such as wood or iron, were employed.

Reference is to be had to the accompanying drawings forming a part of this specification, in which the same characters of reference indicate the same parts in all the 30 views.

Figure 1 is a side view of the framework of my improved unsinkable boat; Fig. 2 is a top plan thereof, showing the same with 35 the coverings in position; Fig. 3 is a sectional view on the line 3—3 of Fig. 2; Fig. 4 is a side view of the framework of another form; Fig. 5 is a top plan of the parts shown in Fig. 4, the dotted lines showing the position assumed by the walls of the air-tight 40 compartments when the same are inflated; and Fig. 6 is a transverse sectional view on the line 6—6 of Fig. 5.

On the drawings, referring to Figs. 1, 45 2 and 3, the numeral 1 indicates the keel of the framework or hull, and this keel has an upturned forward end 2, forming the cut-water of the bow of the boat, and having a rear portion 3. The upper end of the fore 50 part 2 of the keel 1 and the rear part 3 are united by the gunwales 4, and the gunwales

4 are supported above the keel and on each side of the same by means of a plurality of ribs 5. The entire framework of the hull of the boat may be molded in one piece for 55 small craft, or made in sections for larger craft and united together by rivets, bolts or cement, according to the choice of the builder.

The deck of the boat is indicated at 6, 60 and it is shown as having an opening or cockpit 8 surrounded by a coaming 7. The rudder is shown at 9 at the stern, and it is controlled by means of a tiller 10. A motor 11 having a propeller shaft 12, is used to 65 supply the power to run the boat, but it is obvious that I may use sails or oars if desired.

The framework of the hull is covered inside with sections of rubber cloth 13, which 70 are secured to the keel, the gunwale and the ribs. These sections are made waterproof and air-tight; and the adjacent edges of the sections are cemented together to avoid the possibility of leakage. The outside of the 75 boat, on the other hand, from the lower edge of the gunwales down to the keel 1, is covered with sheets of rubber or other elastic material, shown at 14, and these sheets 14 must be both waterproof and air- 80 tight and capable of stretching to a certain extent when the boat is in use. These sheets 13 and 14 form a number of longitudinal air compartments between the ribs 5; and when these air compartments are filled with 85 air, the rubber sheets 14 are forced outward, as shown in Fig. 2, thus greatly increasing the buoyancy of the boat.

Along the gunwales 4 are arranged compartmental tubes 15, also made of sheet rubber or some other material having the same properties; and 16 are valves which are employed to admit air to inflate the compartments formed by the sheets 13 and 14, and the compartments of the tubes 15 as well. 90 95

The seats are shown at 17, arranged along the sides of the cockpit 8; and 18 is a floor. The seats 17 may also be in the form of pneumatic cushions inflated by air the same as the air chambers at the sides of the hull. 100

Figs. 4, 5 and 6 illustrate a boat having a hull made of a somewhat different shape.

In this form a keel 19 is connected by means of ribs 21 to longitudinal braces 22 on each side, into which the keel merges at its opposite ends. These longitudinal braces 22 are connected by an upper series of longitudinal ribs 20 to the gunwales 4. The inside of the framework or hull is covered by means of sheets of rubber cloth 23, the same as the sheets of rubber cloth 13 on the other views. 5

10 These sheets extend from the gunwale down to the keel; and the outside of the boat is covered with sheets of rubber cloth 24' which extend from the keel up to the longitudinal braces 22 on each side. From these braces 15 22 up to the gunwales 4 extend pieces of sheet rubber or other elastic material 24, the inside and outside sheets forming two series of longitudinal air chambers, one series being arranged above the other on each side of 20 the boat, as plainly appears from Figs. 4 and 6. The sections of sheet rubber 24 and the sections of rubber cloth 23 and 24' are, of course, cemented together along adjacent edges to make the air compartments perfectly air-tight; and whenever it is desired 25 to increase the buoyancy of the boat the air is pumped into the upper series of compartments on each side of the boat through valves 25. This will stretch the sections of 30 sheet rubber shown at 24, forcing them out into the dotted-line position shown in Figs. 5 and 6, and thus greatly increasing the amount of water displaced and the buoyancy of the boat.

35 It will be obvious that I may also employ waterproof canvas or other strong waterproof fabric as an additional protecting cover for the inside and outside of both forms of boat shown. This protecting cover 40 will overlie the sections 13 and 14 forming the air compartments for the hull of the boat shown in Figs. 1, 2 and 3, as well as the compartmental tube 15; and will overlie also the sectional sheets 23, 24 and 24' in 45 the form shown in Figs. 4, 5 and 6. Such a covering would make the boat last longer, and would in no way interfere with or diminish the increase in the buoyancy of the craft when the air compartments are inflated, which is one of the chief objects of 50 my invention.

From the above description it will be apparent that a boat made in the manner set forth can have a very great carrying capacity in proportion to its weight, and can be propelled at greater speeds than ordinary boats. At the same time, the boat itself 55 will be strong and able to resist shocks and damage in case of collision with other boats or impediments in the channel, because of the yielding and resilient nature of the material employed in making it. Should the boat, for example, run against a snag, the sheets 14, 15, 24 or 24' would merely yield 60 inward to some extent, stopping the boat 65

and causing it to rebound without damage; and this result can be further insured in case I use the protecting covering of stout canvas or other coarse fabric in the manner above mentioned.

70 The chambers are made perfectly air-tight and are independent one from the other; and even should one or more ever become punctured or damaged, the remaining ones will be sufficient to enable the boat to remain 75 afloat long enough to carry its occupants to shore.

I may employ a number of iron weights to ballast the boat and keep the same on an even keel. Both forms of boat shown are 80 provided with two longitudinal rows of air-tight compartments one above the other on each side of the boat; and the upper rows of compartments when pumped full of air serve not only to increase the buoyancy, but 85 on account of their location they also serve to assist in the important function of trimming or ballasting the craft.

I wish to have it understood that I may 90 make certain small changes in the details of the above-described construction, such as fairly fall within the scope and spirit of my invention.

Having thus described my invention, I claim as new and desire to secure by Letters 95 Patent:

1. An unsinkable boat comprising a framework or hull of hard rubber, having a number of sheets of air-tight and waterproof material secured thereto on the inside and outside thereof, said sheets forming air compartments which increase the buoyancy of the 100 said boat.

2. An unsinkable boat comprising a framework or hull of hard rubber, having a plurality of sheets of air-tight and waterproof material secured thereto on the inside and outside thereof, said sheets forming a plurality of longitudinal rows of air compartments arranged one above the other on each 105 side of the boat, to increase the buoyancy thereof.

3. An unsinkable boat comprising a hull or framework of hard rubber, a plurality of sheets of air-tight and water-proof material 110 secured to said hull on the inside and outside thereof between the gunwale and the keel, said sheets forming a longitudinal row of air compartments on each side of said boat, and a tube of elastic material secured along 115 each side of the framework or hull at the level of the gunwale, forming an additional series of air compartments on each side of the boat, to increase the buoyancy of the craft still further and balance the same.

4. An unsinkable boat comprising a hull or framework of hard rubber, said framework comprising a keel, gunwales above the keel and longitudinal braces between the keel and gunwales on each side, a plurality 120

of ribs connecting the braces, the gunwales and the keel together, and a plurality of sheets of air-tight and waterproof material secured to the inside and outside of said framework and forming two longitudinal rows of air-tight compartments, one above the other, on each side thereof, the upper row of said compartments having extensible outer walls which both increase the buoy-

ancy of the boat and aid in balancing the 10 same.

In testimony whereof I have signed my name to this specification in the presence of two subscribing witnesses.

JOSEPH PASTOREL.
